HOLDER FOR A MILK CARTON

Frank E. Dunkle, Hawthorne, Calif.

Application July 19, 1954, Serial No. 31,479

Term of patent 14 years

(Cl. D58—26)

Fig. 1.

Fig. 2.

Fig. 3.

I claim:

The ornamental design for a holder for a milk carton, substantially as shown.
